UNITED STATES PATENT OFFICE.

LUDWIG DOEDERLEIN, OF CINCINNATI, OHIO, ASSIGNOR, BY DIRECT AND MESNE ASSIGNMENTS, TO TYPEWRITER IMPROVEMENT COMPANY, OF STAUNTON, VIRGINIA, A COPARTNERSHIP.

TYPE-WRITER.

SPECIFICATION forming part of Letters Patent No. 782,111, dated February 7, 1905.

Application filed July 1, 1903. Serial No. 163,922.

To all whom it may concern:

Be it known that I, LUDWIG DOEDERLEIN, a resident of Cincinnati, Ohio, have invented a new and useful Improvement in Type-Writers, 5 which invention is fully set forth in the following specification.

This invention relates to type-writers, and more particularly to line-spacing mechanism therefor.

10 The object of the invention is to provide means whereby the platen will be automatically shifted upon the return of the carriage to its normal position and also to provide mechanism controlled from a key on the finger-board whereby the platen may be shifted without returning the carriage to its normal position.

With these objects in view the invention consists in a type-writer of any usual construction 20 provided with a reciprocating carriage and key-levers which operate to actuate the type and at the same time operate the escapement whereby the carriage is fed with a step-by-step movement in ways well known in the art. 25 Said carriage is provided with mechanism operated at the termination of the return movement of the carriage to actuate a pawl-lever engaging the usual ratchet upon the platen to revolve it.

30 Furthermore, the invention consists of a key-lever extending to the keyboard and having operative connections with the lever controlling the pawl for actuating the ratchet on the platen, to the end that the platen may be 35 shifted from the keyboard without regard to the position of the carriage.

As herein shown, the invention is associated with an automatic carriage-return device controlled by a lever from the keyboard, where- 40 by the carriage may be automatically returned to its normal or extreme right-hand position and the line-spacing mechanism automatically operated by simply touching the key of the carriage-return lever on the keyboard.

45 The inventive idea may receive various mechanical expressions, one of which is illus- trated in the accompanying drawings, in which—

Figure 1 is a rear elevation. Fig. 2 is a

right-hand end elevation. Fig. 3 is a detail 50 perspective of the line-spacing device; and Fig. 4 is a part-sectional view taken on the line 4 4, Fig. 3, looking to the left. Fig. 5 shows certain details in perspective.

Referring to the drawings, on any suitable 55 framework 1 is mounted a bail-piece 2, pivoted in the rear part of the frame, which bail-piece is depressed by the action of the key-levers 3 in striking any given key.

4 is a lever pivoted at 5 to the framework 60 of the machine, which lever has one of its arms connected to the bail-piece 2 by any suitable connecting device, here shown as a yoke 6 and the swivel-link 7. The opposite end of the lever 4 carries a pawl 8, engaging a 65 ratchet-wheel 9 on the shaft 10, having bearings in the framework of the machine. The ratchet-wheel 9 and the pinion 11 are keyed to such shaft, and the pinion engages a gear-wheel 12 upon spring-drum 14, to which drum 70 is connected a pulley 15, over which extends a suitable cable 16, having one end secured to the periphery of the pulley and the other end secured at 17 to the carriage of the machine. In addition to the actuating-pawl 8 a retaining-pawl 18 is pivoted in such position as to engage the ratchet-teeth on the ratchet-wheel 9 and retain it while the pawl 8 is in the act of moving for reengagement with the ratchet-wheel. The lever 4 has a spring 19, normally 80 operating to hold the end of the lever supporting the pawl 8 depressed.

The operation of the mechanism thus far described will be readily understood. When the lever 3 is depressed from the keyboard, it 85 operates to depress one end of the lever 4 and elevate the opposite end bearing the pawl, which thus turns the ratchet-wheel and (through the intermediate clockwork-gearing) winds the spring in the spring-drum 14 and 90 at the same time operates to unwind the cable 16 over the pulley a sufficient distance to permit the carriage to be advanced from the right to the left by the ordinary carriage-advancing spring 20.

Pivoted upon the framework of the machine at 21^b is a lever 21, one of whose arms extends forward to the keyboard and carries

a key 22, while the rear end of the said lever extends under the tails of the pawls 8 and 18, so that when the key 22 is depressed the rear end of the lever is elevated and operates to 5 trip the two pawls 8 and 18 and free the spring in the spring-barrel 14, whereupon it reacts to wind the cable 16 upon the pulley 15 and withdraw the carriage from left to right, this operation being secured by virtue of the 10 fact that the spring in the spring-drum 14 is strong enough to overcome and rewind the ordinary carriage-actuating spring 20. It is, however, frequently desirable in the operation of the machine to shift the carriage in 15 either direction without returning to its extreme right-hand position, and in the act of doing this the operator elevates the rack-bar 27 of the machine, so as to enable the carriage to be shifted from left to right or right 20 to left, as may be desired. In order that this movement may be accomplished, means are provided in the present invention whereby the pawls 8 and 18 shall be tripped and freed from engagement with the ratchet-wheel 9 25 whenever the rack-bar is thus elevated by the operator. For this purpose the bell-crank lever 24 is pivoted to the frame at 25 and has one arm pivotally connected to a slide 26, which extends upward and is provided with a 30 lip 26^a, Fig. 3, overhanging the top of the rack-bar. The other arm of the bell-crank lever 24 is connected by a rod 28 to a crank-arm 29 on a shaft 30, which shaft also carries a wheel 31, having a projecting pin 32 lying 35 normally under the tails of the pawls 8 and 18. Upon elevating the rack-bar 27 the connecting parts are operated to cause the pin 32 to engage pawls 8 and 18 and free them from the ratchet-wheel 9.

40 The lever 21 is normally held in its elevated position by a spring 21^a, and to insure that the lever shall remain depressed and the pawls 8 and 18 disengaged from the ratchet-wheel 9 until the carriage has fully returned to its 45 right-hand position any suitable catch 23 may be employed for engaging and retaining the rear end of the lever elevated until the terminal movement of the carriage to the right, when said catch may be automatically tripped 50 through the medium of a trip-rod 23^a.

For the purpose of rotating the platen to secure the proper line-spacing a lever 34, Figs. 3, 4, and 5, is pivoted upon the carriage at 33 and bears at one end a pawl 35, engaging the 55 ratchet-wheel 36 upon the platen, so that the oscillations of the lever 34 may cause the pawl 35 to engage the ratchet, and thereby turn the platen with a step-by-step movement. The lever 34 may be caused to oscillate in any suitable manner. The mechanism here shown for that purpose consists of a forked bar 37, pivotally connected to link 37^a, whose other end is pivoted to the carriage at 37^b, so that the bar 37 is free to move up and down vertically on 60 the carriage, with the rear end of the lever 34

resting in the fork of the bar 37 and upon an antifriction-roller 38, carried by said bar. On the link 37^a is a cam finger-piece 39, pivoted thereto with a knuckle-joint, and upon a stationary part of the machine is located an abutment 40, preferably in the form of an antifriction-roller and in the path of the cam 39 as the carriage moves from left to right. Preferably this abutment 40 is supported on the usual carriage-return stop 40^a, so that it is 75 always in position to actuate the platen-turning lever 34 just before the termination of the return movement of the carriage.

The action of the mechanism thus far described is as follows: Just before the carriage finishes its movement from left to right the cam 39 strikes the abutment 40, thereby causing the forked bar 37 to be elevated, carrying with it the rear end of the lever 34 and depressing the opposite end of the lever which carries the pawl 35 and causing the latter to turn the platen. It will be observed that this action is entirely automatic and takes place whether the carriage is returned by means of the automatic return devices herein-before described or whether it is returned by the hand of the operator.

In the mechanism, however, as thus far described the platen would only be actuated upon the full throw of the carriage from left to right, and as it is frequently desirable to shift the platen without making this return movement of the carriage means are provided whereby the operator may readily rotate the platen by touching a key-lever at the 95 keyboard without regard to the position at that time occupied by the carriage.

Referring to Fig. 3, 41 is a lever pivoted at 42 to any suitable part of the framework of the machine and having its forward end 105 extending to the keyboard, while its rear arm is connected by a link 43 to one arm of a bell-crank lever 44, pivoted at 45 to the framework and pivotally connected to a lever 46, moving in a substantially horizontal plane 110 around the fulcrum 47. The forward end of the lever 46 has an arm 48 pivoted thereto, which arm extends under a swinging bar or blade 49, pivotally mounted in bearings 50 on the carriage, said arm 48 having an upwardly-projecting part bearing an antifriction-roller 51 in front of the swinging bar 49. Rigidly secured to the bar 49, and preferably integral therewith, is a forwardly-extending arm or lever 52, having a laterally-extending pin 53, bearing upon the forward arm of lever 54, fulcrumed at 55 on the carriage. The lever 54 has on its rear arm a laterally-extending pin 56, (see Fig. 5,) which normally rests under the rearwardly-extending arm of the pawl-lever 34. 125 As the carriage reciprocates back and forth the plate 49 is moved past the antifriction-roller 51, with the latter always in front of the plate, and by depressing the front end of the lever 41 the operator will actuate the connect- 130

ing-lever mechanism so as to produce a rearward pull upon the link 48 and cause the plate to so vibrate upon its bearings as to depress the lever 52, and with it the forward end of the lever 54, thereby elevating the rear end of the lever 54, and this engages and operates the pawl-lever 34. It will therefore be seen that in any position which the carriage may occupy on the machine the operator may readily 10 rotate the platen by simply touching the key connected to the key-lever 41.

In order that the platen may be free to be shifted by hand either backward or forward, as may be necessary, means are provided for 15 automatically withdrawing the pawl 35 from engagement with the ratchet 36, except when the same is in the immediate act of rotating the platen.

Referring to Figs. 3, 4, and 5, 57 is a lever 20 pivoted on the same fulcrum 33 as the pawl-lever 34. This lever 57 is provided with a cam-face 58, lying in front of a pin 59 on the pawl-lever, the portions of the cam being such that any upward movement of the pawl with relation to the cam-surface 58 will result in swinging the pawl rearwardly. The rear end of the pawl-lever 34 is normally held depressed by the action of a spring 60, bearing thereon, which serves to elevate the forward or pawl- 25 bearing end of the lever, while the cam-lever 57 is also elevated by means of a flat spring 61 underlying the lever, the spring 60, however, being stronger than the spring 61. As shown in Fig. 4, the forked bar 37 is elevated and the 30 pawl 35 has just reached the limit of its downward stroke. Upon the forked bar 37 being lowered the spring 60 will act to elevate the pawl 35, and the pin 59 thereon, engaging the cam 58 on the lever 57, will act to swing the 35 pawl rearward and out of engagement with the teeth of the ratchet 36, the lever 57 being prevented from moving upward with the pawl-lever 34 by reason of a stop-pin 62 projecting through an opening in a part of the frame-work above the two levers 34 and 57, so that the upward movement of 57 is stopped before that of the lever 34, the relative movement of the two levers securing the travel of the pin 59 along the cam 58. For the purpose of adjusting 40 the pawl-lever so as to cause the pawl 35 to engage every tooth or every other tooth, as may be desired for either single or double-line spacing, means are provided whereby the stop-pin 62 may be adjusted into a higher or 45 lower position. For this purpose the stop-pin is mounted upon a pivoted arm 63 and is normally provided with a spring 64 for holding it pressed inward and a button 65, which may be grasped for the purpose of withdrawing the 50 pin in the act of adjustment. As shown in Fig. 3, the stop-pin is in the lower one of the holes in the frame, and the pawl would act to shift the platen for single spacing. By shifting the pin to the opening 66, however, the

pawl will be allowed to rise far enough so as 55 to skip one ratchet-tooth and engage only every other tooth on the ratchet-wheel, while the lever 34 will have a greater throw, thereby shifting the platen for double spacing.

It will be understood that while I have 70 herein shown the pivoted bar 49 as a substantially vertical bar this is not essential, as any swinging bar positioned so as to be operatively engaged by shifting means actuated by the key-lever will be within the spirit of 75 the invention, provided said swinging bar operates to actuate the pawl-lever for shifting the platen.

For the purpose of operating the pawl-lever 80 34 to manually rotate the platen without actuating the key-lever 41 or moving the carriage-return mechanism a finger-rest or thumb-piece 67 may be and preferably is secured to the forward end of said pawl-lever 85 34, to be pressed by the finger of the operator 5 to effect the desired result. (See Figs. 4 and 5.)

While I have herein shown and described the automatic carriage-return mechanism and have claimed the same broadly in combination with the line-spacing devices, I have 90 not claimed the same specifically herein, as it will form the subject-matter of a separate application, Serial No. 165,169, filed July 11, 1903.

I claim—

95

1. In a type-writer, the combination of a reciprocating carriage bearing a platen, platen-rotating devices mounted on the carriage, a pivoted blade carrying an arm located on the carriage and operatively connected to said 100 devices, and a key-lever fulcrumed on a stationary part of the machine and operatively connected to said pivoted member.

2. In a type-writer, the combination of a reciprocating carriage bearing a platen provided 105 with a ratchet-wheel, a pawl-lever pivoted on the carriage and bearing a pawl for engaging said ratchet, a pivoted blade on the carriage, a key-lever operable from the keyboard for operating the blade, and operative connections 110 between said blade and pawl-lever.

3. In a type-writer, the combination of a reciprocating carriage bearing a platen having 115 a ratchet thereon, a lever fulcrumed on the carriage and having a pawl engaging said ratchet, a reciprocating element engaging said lever, and automatic means reciprocating said element consisting of a link pivoted on the carriage, and a knuckle-jointed pivotally-supported cam on said link adapted to engage 120 a stationary part on the carriage-frame.

4. In a type-writer, the combination of a reciprocating carriage bearing a platen provided 125 with a ratchet-wheel, a pawl-lever pivoted on the carriage and bearing a pawl for engaging said ratchet, automatic means for disengaging said pawl from the ratchet-wheel, a pivoted blade on the carriage, a key-lever operable

from the keyboard for operating the blade, and operative connections between said blade and pawl-lever.

5. In a type-writer, the combination of a reciprocating carriage bearing a platen provided with a ratchet-wheel, a pawl-lever pivoted on the carriage and bearing a pawl for engaging said ratchet, a pivoted blade on the carriage provided with an arm, connecting means between said arm and lever for reciprocating the latter, and a key-lever operable from the keyboard for operating the blade.

6. In a type-writer, the combination of a reciprocating carriage, and automatic carriage-return mechanism, with a revolute platen having a ratchet-wheel, a lever carrying a pawl engaging said ratchet-wheel to turn the platen, automatic devices operating said lever, a projection on said pawl, a lever engaging said projection and operated by said first lever whereby the pawl is disengaged after each throw of said lever.

7. In a type-writer, the combination of a reciprocating carriage and automatic carriage-return mechanism, with a rotatable platen having a ratchet-wheel, a lever fulcrumed on the carriage and carrying a pawl engaging said ratchet-wheel, a projection on said pawl, means engaging said projection and operated by said lever for disengaging said pawl after each throw of the lever, a reciprocating member carried on the carriage and engaging said lever, and means reciprocating said member upon the return of the carriage.

35 8. In a type-writer, a carriage, a revolute platen thereon, a vibratory lever, connections between the lever and platen whereby the vibrations of the former turn the latter, automatic means on said lever for disengaging said connections, an oscillating plate or bar on the carriage, operative connections between said bar and lever, and means operable from the keyboard and engaging said plate or bar to oscillate it.

45 9. In a type-writer, the combination of a reciprocating carriage, a rotatable platen there-

on, a swinging blade or bar extending longitudinally of the carriage and provided with an extending arm, a lever having a part in position to engage and swing said blade or bar, a key on the keyboard operatively connected to said lever, and platen-rotating mechanism operatively connected to said arm on the swinging blade or bar.

5. In a type-writer, the combination of a reciprocating carriage, a revolute platen thereon provided with a ratchet-wheel, a lever pivoted on the carriage and provided with a pawl for engaging the ratchet, a pivoted blade on the carriage, operative connections between said blade and lever, an antifriction-roller and a key-lever for operating the same, whereby said blade may be oscillated in any position of the carriage.

10. In a type-writer, the combination of a reciprocating carriage, a revolute platen thereon provided with a ratchet-wheel, a lever pivoted on the carriage and bearing a pawl, an adjustable stop for said lever, means for normally holding said lever against said stop, a second lever adapted to be actuated by the first lever and provided with a cam-face for engaging said pawl whereby the pawl is disengaged from the ratchet-wheel after each throw of the said first lever.

11. In a type-writer, the combination of a reciprocating carriage bearing a platen provided with a ratchet-wheel, a lever pivoted on the carriage and bearing a pawl, an adjustable stop for said lever, means for normally holding said lever against said stop, a second lever adapted to be actuated by the first lever and provided with a cam-face for engaging said pawl whereby the pawl is disengaged from the ratchet-wheel after each throw of the said first lever.

12. In a type-writer, the combination of a revolute platen having a ratchet-wheel, a lever carrying a pawl, a second lever actuated by the first and provided with means for engaging said pawl whereby the said pawl is disengaged from the ratchet-wheel after each throw of the lever, adjustable means for stopping said levers successively and a spring for holding said levers normally against said stopping means.

75 In testimony whereof I have signed this specification in the presence of two subscribing witnesses.

LUDWIG DOEDERLEIN.
